UNITED STATES PATENT OFFICE.

ROBERT L. COMMONS, OF HARVEY, ILLINOIS.

HEATING STOVE OR FURNACE.

No. 827,963.

Specification of Letters Patent.

Patented Aug. 7, 1906.

Application filed June 23, 1905. Serial No. 266,598.

To all whom it may concern:

Be it known that I, ROBERT L. COMMONS, a citizen of the United States, residing at Harvey, in the county of Cook and State of Illinois, have invented certain new and useful Improvements in Heating Stoves or Furnaces; and I do hereby declare that the following is a full, clear, and exact description thereof, reference being had to the accompanying drawings, and to the letters of reference marked thereon, which form a part of this specification.

This invention relates to improvements in heating stoves or furnaces; and the invention consists in the matters hereinafter set forth, and more particularly pointed out in the appended claims.

Among the objects of the invention is to provide an exceedingly simple stove which can be economically manufactured and which possesses high heating efficiency.

In the drawings, Figure 1 is a vertical section of a stove made in accordance with my invention, taken on line 1 1 of Fig. 5. Fig. 2 is a top plan view thereof. Fig. 3 is a vertical section of the stove, taken on line 3 3 of Fig. 5. Fig. 4 is a transverse section taken on line 4 4 of Fig. 1. Fig. 5 is a transverse section taken on line 5 5 of Fig. 1. Fig. 6 is a top plan view, partially broken away, showing a modified form of the stove.

As shown in the drawings, the main body of the stove consists of an outer shell A and an inner shell C. Within the lower part of the outer shell is formed a fire-pot A', provided with the usual grate A², and A³ is a door closing the fire-pot. B designates the base of the stove, which incloses an ash-pan B', which is adapted to be withdrawn from the side of the base.

In the construction shown in Fig. 1 the inner shell constitutes a combustion-chamber, which is closed at its top by an end wall c and is in open communication at its lower end with the fire-pot A'. Between said inner and outer shells are formed alternating smoke-flues D and air-passages E. Said alternating air-passages and smoke-flues are separated by partitions a a, which extend from the lower end of the shell C to the top wall A⁴ of the stove. The smoke-flues are open at their lower ends to the fire-pot and communicate at their upper ends with a central pipe-nipple A⁵, rising from the top of the stove through the medium of horizontal radially-disposed conduits D', Fig. 2, formed on the

top wall of the stove. Preferably the smoke-flues communicate at their upper ends with the interior of the shell C through openings c', so as to avoid a pocket or dead-gas space 60 in the top of the inner shell and to promote combustion.

The air-passages E receive air through openings e at the lower ends thereof, and currents of air rise through the passages and are 65 discharged from the upper ends thereof into the space surrounding the stove through openings e' in the top wall of the stove. Preferably said air-passages E extend at their lower ends below the lower ends of the smoke-flues and are inclosed, within the fire-box, by the outer shell A and the inner walls e² and constitute pockets, into which the air is received through the inlet-openings e. With this construction the cooler air near the floor 70 of the room containing the stove is drawn into the air-passages, thereby promoting the circulation of the air through said passages. Moreover, the extension of said passages into the fire-box in the manner described brings 75 the said lower ends of the flues into intimate contact with the heat of the fire-box, thereby adding to the efficiency of the transmission of the heat to the rising air-currents. The walls of said air-passages between the shells 80 85 are formed by the partitions a a at their lateral sides and by the shells A and C at their outer and inner sides, respectively. The alternate arrangement of the smoke-flues and air-passages is an important feature of the 90 construction, inasmuch as such construction brings the heated products of combustion in contact with three sides of the air-passages, through which the heat is transmitted to the air-currents rising upwardly through said 95 passages.

Preferably the air-passages E are made smallest at their lower ends and gradually increase in cross-sectional area toward their upper ends, while the smoke-flues D are 100 reversely disposed, being made widest at their lower ends and narrowest at their upper ends. Such arrangement of the flues is clearly shown in Figs. 1 and 2 and will be understood from a comparison of Figs. 4 and 5, Fig. 5 illustrating the width of said passages at their lower ends and Fig. 4 illustrating the width thereof at their upper ends. Such variation of the width of the smoke-flues and air-passages is effected by inclining the partitions 105 toward and away from each other. The inclination of the side walls of the air-passages 110

from each other toward the upper ends of the passages increases the width of the inner walls of said passages formed by said shell C, whereby the currents of air rising through 5 the passages are brought in contact with gradually-increased extent of said inner walls, with the result of an increased transmission of heat to said rising air-currents. The construction described, while increasing the area 10 of the inner walls of the passages against which the rising air-currents are brought into contact, has no effect to increase or diminish the area of the side walls of the passages constituted by said partitions *a*.

15 As herein shown, the stove is provided with three smoke-flues D and three air-passages E; but the number thereof may be varied as desired. One of the air-passages E—to wit, that on the side of the stove adjacent to the 20 door—is herein shown as made considerably wider than the other two passages and is provided at its upper end with two discharge-openings *e'*, Fig. 2. Said wide air-passage may also be provided at its lower end with 25 two extensions located in the fire-box and communicating with the inlet air-openings *e*. This construction provides at the upper end of the stove a space to receive irons or other articles to be heated thereon. The door is 30 located partially above the level of the lower end of the inner shell C, whereby that part of the shell in front of the upper part of the door constitutes a shield located between the upper part of the door-opening and the fire-box. 35 The space in front of said door-opening is separated from the wider air-passage by a horizontal partition *d*, Figs. 1 and 4. As a preferred construction the inner and outer shells and the partitions dividing the smoke-flues and air-passages, as well as the top wall 40 of the stove, are made of an integral casting, the integral casting extending to the base of the stove and joined thereto by an offset joining-margin, as shown in Figs. 1 and 3. Baffle-bars *d'* are shown as extending across the 45 lower ends of the smoke-flues D to break up the currents of smoke upon entering said flues.

In Fig. 6 I have shown a modified form of 50 the stove, wherein the fuel-opening *A*⁶ is formed in the top wall *A*⁴ of the stove and is closed by a suitable lid or cover *A*⁷. In this construction the pipe-nipple *A*⁸ is located at one side of the stove-top and communicates 55 with the smoke-flues of the furnace through conduits *A*⁹ *A*¹⁰, the rear one, *A*⁹, of which opens directly into the pipe-nipple and the side ones, *A*¹⁰, of which extend laterally and rearwardly to said nipple. Said conduits, as 60 well as the pipe-nipple, are formed integral parts of the stove-top and operate in the same manner as do the conduits *D'* of the previously-described construction to direct the smoke rising through the passages D to 65 the pipe-nipple *A*⁸.

In some instances the stove herein shown may be used as the central furnace of a hot-air heating system. In such use suitable air-pipes may conduct the heated air from the 70 passages E to the different rooms or apartments to be heated. For this purpose nipples are shown as rising from the stove-top around the discharge-openings *e'* of said passages, to which the distributing-passages may be attached.

75

I claim as my invention—

1. A stove comprising inner and outer shells between which are formed alternate, vertical smoke-flues and air-passages, a fire-box formed in the lower part of the outer shell and communicating with the lower ends of the smoke-flues, and a pipe-nipple into which the upper ends of the smoke-flues discharge, said air-passages receiving air at 80 their lower ends through openings in the said outer shell and provided with discharge-openings at their upper ends.

85

2. A stove comprising inner and outer shells between which are formed alternate, vertical smoke-flues and air-passages, a fire-box formed in the lower part of the outer shell and communicating with the lower ends of the smoke-flues, and a pipe-nipple into which the upper ends of the smoke-flues discharge, said air-passages receiving air at 90 their lower ends through openings in the said outer shell and provided with discharge-openings at their upper ends, said air-passages being made narrow at their lower ends and increasing in cross-sectional area to 95 toward their upper ends.

100

3. A stove comprising inner and outer shells between which are formed alternate, vertical smoke-flues and air-passages, a fire-box formed in the lower part of the outer shell and communicating with the lower ends of the smoke-flues, and a pipe-nipple into which the upper ends of the smoke-flues discharge, said air-passages receiving air at 105 their lower ends through openings in the said outer shell and provided with discharge-openings at their upper ends, said air-passages extending at their lower ends below the smoke-flues and into the fire-box.

110

4. A stove comprising inner and outer 115 shells closed at their upper ends between which are formed alternate, vertical smoke-flues and air-passages, a fire-box formed in the lower end of the outer shell and communicating with the lower ends of the smoke-flues, and a pipe-nipple into which the upper ends of the smoke-flues discharge, said air-passages receiving air at 120 their lower ends through openings formed in said outer shell and provided with discharge-openings at 125 their upper ends, said inner shell being provided near its upper ends with apertures which open into the upper ends of the smoke-flues.

5. A stove comprising inner and outer 130

shells, a fire-box, partitions extending between and integral with said inner and outer shells and forming vertical passages between said shells, the alternate passages constituting air-passages and smoke-flues, which latter communicate at their lower ends with said fire-box, and a pipe-nipple communicating with the upper ends of said smoke-flues, said air-passages receiving air at their lower ends 5 through openings formed in said outer shell and provided with discharge-openings at their upper ends.

6. A stove comprising inner and outer shells, a fire-box, partitions extending between and integral with said inner and outer shells and forming vertical passages between said shells, the alternate passages constituting air-passages and smoke-flues, which latter communicate at their lower ends with 10 said fire-box, and a pipe-nipple communicating with the upper ends of said smoke-flues, said air-passages receiving air at their lower ends through openings formed in said outer shell and provided with discharge-openings at 15 their upper ends, said partitions being inclined from the vertical in such manner that 20 at their upper ends, said partitions being inclined from the vertical in such manner that 25

the air-passages are widest at their upper ends and the smoke-flues are widest at their lower ends.

7. A stove comprising inner and outer shells between which are provided alternate, vertical smoke-flues and air-passages, a fire-box formed in the lower part of the outer shell and communicating with the lower ends of the smoke-flues, a pipe-nipple into which 30 the upper ends of the smoke-flues discharge, said air-passages receiving air at their lower ends through openings in the said outer shell and provided with discharge-openings at 35 their upper ends, said air-passages being made narrow at their lower ends and increasing in cross-sectional area toward their upper ends, and baffle-bars extending horizontally across the lower ends of said smoke-flues.

In testimony that I claim the foregoing as 40 my invention I affix my signature, in presence of two witnesses, this 17th day of June, A. D. 1905.
